UNITED STATES PATENT OFFICE.

CHARLES LEA, OF BOSTON, MASSACHUSETTS, ASSIGNOR TO AMERICAN WARP-DRAWING MACHINE COMPANY, A CORPORATION OF MAINE.

YARN-HOLDER.

1,153,870.

Specification of Letters Patent.

Patented Sept. 14, 1915.

Continuation in part of application Serial No. 533,408, filed December 16, 1909. This application filed July 18, 1912. Serial No. 710,124.

To all whom it may concern:

Be it known that I, CHARLES LEA, a citizen of the United States, and a resident of Boston, county of Suffolk, State of Massachusetts, (whose post-office address is corner of Freeport and Beach streets, Dorchester, Massachusetts,) have invented an Improvement in Yarn-Holders, of which the following description, in connection with the accompanying drawings, is a specification, like characters on the drawings representing like parts.

This invention relates to yarn holding devices employed in connection with the manufacture of carpets or rugs of the Axminster or similar types, being more particularly concerned with the provision of improved means for maintaining the tuft yarns in their established pattern arrangement after being wound on the spool in the spooling machine and until they are drawn through the tubes of the tube frame which is ordinarily employed with carpet looms of this class.

25 The invention will be best understood by reference to the following description when taken in connection with the accompanying illustration of one specific embodiment thereof, while its scope will be more particularly pointed out in the appended claims.

In the drawings: Figure 1 shows in perspective, partly broken away, a yarn holder embodying one form of my invention; Fig. 2 shows the same yarn holder applied to a spool; Fig. 3 shows on a larger scale in plan the construction of one end of the holder; and Fig. 4 shows the same end in side elevation.

35 In the preparation of the tuft yarns for the tubing operation the yarns are wound upon the spool of the spooling machine while held separated by the usual reed or separator and in a prearranged pattern. At such time it is customary to apply to the 40 yarns a toothed comb or holder whereby in transferring the yarns to the tubing machine, they may be maintained in the same separated condition and drawn accurately through the tubes of the tube frame.

45 In actual manufacture, considerable time usually elapses between the spooling operation and the tubing operation. It is customary to wind on a large supply of spools in advance of actual requirements and these

spools are then stored away and may be 55 kept for long periods of time before they are placed in the tubing machine. It is, however, requisite that in whatever condition the spools are kept or however long they are kept the yarns be maintained separated in 60 the same fashion as they originally came from the spooling machine. It is also requisite that they be so constructed that when applied to the spool and the latter is stored with other spools, or transferred from one 65 place to another, they have no tendency to catch upon or otherwise disarrange the yarns upon their own or adjacent spools with which they may come in contact.

Referring to Fig. 1, I have there shown a 70 transfer comb or holder 1, preferably formed of sheet metal, and presenting a series of projecting teeth 2, the latter being predeterminedly spaced according to the spacing of the tuft yarns with which the comb is to 75 be employed, which spacing will correspond to the spacing of the reed teeth in the spooling machine and the tubes in the tube frame. This comb may be applied in any suitable manner to the tuft yarns in the spooling 80 machine, so that the yarn will enter between the teeth 2. The lower edge 3 of the comb may be curled over as shown, which causes the comb to present a smooth lower edge and also serves to give stiffness to the comb, and 85 permit its ready application to a suitable holder in the spooling machine.

With the yarns entered between the teeth of the holder, they are then prevented from slipping out of the comb by the application 90 thereto of a cap-piece or retainer 4, the latter consisting preferably of a sheet metal strip bent into a U-shaped cross section and adapted to slip over the points of the teeth and close the mouths of the slits against the 95 exit of the yarn strands. The cap may be so proportioned with reference to the depth of the slits as to clamp the yarns therein, but preferably the slits are deeper than the sides of the cap so that the free, longitudinal 100 draft of the threads between the teeth is not prevented.

The cap-piece may be retained on the comb by suitable means, such for example as the resilient finger 5, one such finger being appropriately secured at each end of the face of the comb. Any suitable means may be employed for securing the resilient fin-

gers in position, but herein each finger is shown as provided with a bottom projection or tang 6. The finger being seated upon the bottom of the groove, the tang projects through an opening 7 in the bent-over edge 3 and a single rivet 8 is provided to hold the finger firmly in place, the tang 6 preventing its displacement. The end of the finger is bent at 9 and prolonged to overlie the end 10 of the cap-piece. To provide a secure fastening for the cap-piece the end of the bend in the finger is curved so as to lie transversely over the cap-piece at 10, and the end of the cap-piece is formed with a shouldered or flattened portion 11 to form a seat for the bent retaining end of the resilient finger. The described construction permits the ready application of the cap to the comb, the fingers easily snapping into position upon 15 the seat on the cap, serving effectively to retain the cap under the severest conditions of usage. The locking finger, however, is sufficiently resilient to permit its projecting portion to be pressed back for the release of the cap and the withdrawal of the latter from 20 the comb or work. With the retaining cap in position the holder may be then attached to the spool by suitable means, so that no matter how much the spool may be handled 25 in transference or how long afterward the tubing operation may be performed, the comb cannot be accidentally displaced.

In the described embodiment of the invention the comb is shown provided at each 30 end with an attachment member, herein in the form of a spring 12. The latter has an eye 13, which may be slipped over the small pintle at the end of the spool 14 and employed to attach the comb to the spool, the 35 former having first been laid flatwise against the wound-on yarn. The comb being drawn flatwise against the wound-on yarn acts as a clamp preventing the unwinding of the yarn from the spool.

40 In order to prevent the entanglement of portions of the comb with the yarn strands, all projecting parts are carefully protected or covered. The bent over edge 3 and the U-shaped cap provide smooth edges for the 45 comb. At the ends the projecting corners are rounded at 15 and 16, as is also the corner 17 of the resilient finger, and the corner 18 of the cap. The retaining member 10 of the finger is also rounded, as is the shoul- 50 dered portion of the cap seat, so that there are left no pointed projections apt to catch in the yarn. This provides a yarn holder which may be used in connection with the spools with entire safety and security.

55 While I have herein shown and described one specific embodiment of my invention for illustrative purposes, it is to be understood that the invention is not limited to the constructional details herein shown, but that 60 extensive deviations may be made from the

form herein shown without departing from the spirit of the invention.

Claims.

1. A holder for tuft yarns having a toothed comb formed of sheet material, a cap 70 having a U-shaped cross section for the teeth of the comb, said cap having a recessed seat at each end and a resilient finger secured at each end of the comb and having a portion adapted to project transversely over the recessed end of the cap. 75

2. A transfer comb or holder for tuft yarns for transferring the yarns from the spooling machine in separated and pre-arranged pattern to the tubing machine, comprising a toothed comb between the teeth of which the yarns are adapted to be received, a cap to close the openings between the teeth and a resilient retaining means arranged to overlie transversely an end of the cap. 80

3. A transfer comb or holder for tuft yarns for transferring the yarns from the spooling machine in separated and pre-arranged pattern to the tubing machine, comprising a toothed comb between the teeth of which the yarns are adapted to be received, a cap to close the openings between the teeth and a retaining finger for the cap, the latter being recessed at its end to provide a seat for the finger. 85

4. A transfer comb or holder for tuft yarns for transferring the yarns from the spooling machine in separated and pre-arranged pattern to the tubing machine, comprising a toothed comb between the teeth of 100 which the yarns are adapted to be received, a cap to close the openings between the teeth and retaining means for the cap, the latter provided with a seat for the retaining means.

5. A holder or transfer device for tuft 105 yarns for transferring the yarns from the spooling machine to the tubing machine while held separated in pre-arranged pattern, comprising a toothed comb between the teeth of which the yarns are adapted to be 110 received, said comb having a turned over bottom edge, a resilient retaining finger seated in the groove formed by the turned over bottom edge, and a single rivet for fastening the finger to the holder. 115

6. A holder for tuft yarns having the comb 1 provided with the flanged bottom 3, the cap 4, having the recess 11, the finger 5 having the projecting portion 9. 120

7. A holder for tuft yarns having a toothed comb having a turned over bottom edge, a resilient retaining finger seated in the groove formed by the turned over bottom edge, and means for fastening the finger to the holder. 125

8. A holder for tuft yarns having a toothed comb, a retaining cap and a flat L-shaped resilient finger for the cap, the resilient holder having rounded corners. 130

9. A holder for tuft yarns having a 135

toothed comb formed of sheet metal and provided with a turned-over bottom edge, a cap having a U-shaped cross section for the teeth of the comb, said cap having a recessed seat at each end and a resilient finger seated at each end of the comb in the groove formed by the turned-over bottom edge and having a portion adapted to project transversely over the recessed end of the cap, the corners 10 of said comb and said retaining cap being rounded.

10. A holder for tuft yarns, having a toothed comb provided with a turned-over bottom edge, a resilient retaining finger seat-

ed in the groove formed by the turned-over bottom edge and near the end of the comb, a tang on said finger projecting over an opening in the turned-over portion, and an additional fastening also for said finger to said comb.

In testimony whereof, I have signed my name to this specification, in the presence of two subscribing witnesses.

CHARLES LEA.
